UNITED STATES PATENT OFFICE.

HENRY J. ROTH, OF NEW YORK, N. Y.

SAFETY-RAZOR.

1,176,780.

Specification of Letters Patent. Patented Mar. 28, 1916.

Application filed April 21, 1914. Serial No. 833,346.

To all whom it may concern:

Be it known that I, HENRY J. ROTH, a citizen of the United States, residing in the borough of Brooklyn, county of Kings, city 5 and State of New York, have invented certain new and useful Improvements in Safety-Razors, of which the following is a specification.

This invention relates to improvements in 10 safety razors and particularly to telescoping handles for the same, which are adapted to be easily manipulated and firmly held in open or closed position. The improved handle will be described in connection with 15 a simple form of safety razor apparatus which can effectively be used with the so-called wafer razor blade.

In order that my invention may be more 20 clearly understood, attention is hereby directed to the accompanying drawings forming part of the specification and illustrating the preferred embodiment of my improved apparatus.

In the drawings, Figure 1 represents in 25 side elevation my improved razor with the blade positioned therein and with the telescoping handle in extended position, Fig. 2 represents an enlarged view of the same, part in vertical section and part in side elevation, Fig. 3 is a view similar to Fig. 1 with the telescoping handle in closed position, and Fig. 4 is a section taken on line 4-4 of Fig. 3.

Referring to the drawings, the body of 35 the razor comprises an integral frame 1 having a central web or hub portion 2 arranged in an approximately horizontal plane. This web is provided with a circular central opening in which is mounted the ring 3 which 40 is screw-threaded on its inner surface to receive a screw-threaded end of the handle 4. Extending rearwardly from the central web 2 is a portion 5 of the frame provided at its rear edge with an upturned flange 6. 45 Extending forwardly from the web 2 is a portion 7 ending in the usual comb-like guard 8. The portion 5 of the frame referred to, which extends rearwardly from the central web 2, has integral therewith a 50 rear cross portion extending the width of the frame, side portions 10, and a front cross portion extending across the frame in front of the central web 2, the comb 8 being formed on the forward portion of this front cross portion. The side portions 10 and 55 transversely extending portions referred to

are inclined at a suitable angle to form a supporting surface for a wafer razor-blade, which thus extends forwardly, when mounted on the holder in position for use at an 60 acute angle to the axis of the handle 4.

The upwardly extending rear flange 6 is provided with openings through which set screws 6' are adjusted to form an adjustable abutment against which the rear edge of 65 the razor-blade is positioned. Set screws 6' extend above the rear cross portion of the frame and closely adjacent thereto, flange 6 only extending above the set screws a sufficient distance to form a proper bearing surface therefor. In devices of this character as previously constructed, a flange similar to flange 6 has been extended upwardly so far as to interfere with the operation of 70 shaving.

The razor-blade is positioned by means of lugs 13 extending upwardly from the side edges of side portions 10 of the frame, and adapted to receive the side edges of the razor-blade. The blade is clamped when 80 positioned between lugs 13 by means of pivoted arms 14 which are pivoted to the rear surfaces of side portions 10 of the frame, these arms having upwardly and transversely extending portions 15 on their free 85 ends adapted to extend over and clamp the side edges of the razor-blade when the same is positioned on the frame. To accomplish the proper position of lugs 15 to coöperate with a wafer razor-blade as intended, arms 90 14 are bent at a somewhat sharper angle than side-members 10 of the frame. The details of the frame construction are not claimed herein, but only the handle.

The handle 4 is provided with a longitudinal slot 16 extending for the full length of the shaft 4 between the lower end 17 thereof and the screw-threaded portion of reduced diameter on the other end which is adapted to be screwed into the central opening of the frame 1. A sleeve 18 is mounted on shaft 4 to be telescopically extended to form a handle of the desired length or to be pushed into closed position when the razor is to be packed in a box. Sleeve 18 is 105 provided with an inwardly extending projection 19 adapted to fit within slot 16 when sleeve 18 is in its inner or closed position, projection 19 being formed by simply punching or pressing the metal of the sleeve 110 inwardly at the desired point. When the sleeve is extended into its open position so

that projection 19 has passed beyond the end surface 17 of the shaft, the sleeve can be rotated a portion of a revolution so that projection 19 coacts with the end surface 17 of the shaft 4 to prevent inward movement of the sleeve. The sleeve 18 also has its forward edge 20 bent inwardly to a slight extent as shown and shaft 4 is given a correspondingly increased diameter as shown at 10 21 for a portion of its length adjacent to end 17 of the shaft. The length of the flange or raised portion 21 of the shaft is preferably slightly less than the distance between the projection 19 and the inwardly 15 turned edge 20 of the sleeve, the result of this construction being that when the sleeve has been extended into its outer position and rotated, the projection 19 coacts with surface 17 to prevent inward movement of the sleeve and the inwardly turned edge 20 of the sleeve coacts with the raised edge of the 20 enlarged portion 21 of the shaft to prevent further outward movement of the sleeve, which latter is thereby locked against axial 25 movement either up or down the shaft 4.

Having now described my invention, what I claim and desire to protect by Letters Patent is as follows:

1. In a safety razor, the combination of 20 a handle comprising a cylindrical shaft adapted to be secured to the blade-holder of the razor having a longitudinal groove extending throughout its length, and being formed with a circumferential flange adja-

cent its lower end, and a sleeve mounted to 35 telescope upon said shaft, provided with an inwardly-extending projection integral with and pressed from the metal of the sleeve, adapted to slide in said groove and to press against the rear end of said shaft when said 40 sleeve is in extended position and is rotated about said shaft, with said projection removed from said groove, the forward end of said sleeve being provided with an inwardly-extending flange adapted to coact 45 with said shaft flange when said sleeve is in extended position, substantially as set forth.

2. In a safety razor, the combination of a handle comprising a cylindrical shaft, and a sleeve mounted thereon and adapted to slide thereon into closed and extended positions, said shaft and sleeve being formed with coacting means, integral therewith, for locking said sleeve in its extended position against movement longitudinally of said 55 shaft either up or down, said means comprising a collar portion at the end of said shaft and inwardly extending projections on said sleeve adapted to contact both upper and lower surfaces of said collar portion when said sleeve is arranged in its extended position, substantially as set forth.

This specification signed and witnessed this 20th day of April, 1914.

HENRY J. ROTH.
